V. HAMILTON

PUMP BARREL

Filed Sept. 20, 1922

Van Hamilton
INVENTOR

BY *Victor J. Evans*
ATTORNEY

Bill Markward
WITNESS:

UNITED STATES PATENT OFFICE.

VAN HAMILTON, OF ELDORADO, KANSAS.

PUMP BARREL.

Application filed September 20, 1922. Serial No. 589,422.

To all whom it may concern:

Be it known that I, VAN HAMILTON, a citizen of the United States, residing at Eldorado, in the county of Butler and State of Kansas, have invented new and useful Improvements in Pump Barrels, of which the following is a specification.

In oil wells, when the tubing is pulled, the oil that remains in the tubing is permitted to flow on to the ground and is therefore a complete loss. It is the object of this invention to produce a device designed to be connected to the working barrel of an oil well pump whereby the oil may be pumped into the well and thus saved when the tubing is drawn outwardly thereof.

The drawing, which accompanies and forms part of this application, illustrates a satisfactory embodiment of the improvement reduced to practice, and wherein:

Figure 1 is an elevation with parts in section, illustrating the improvement connected to the working barrel of an oil well, the device being in pumping position.

Figure 2 is a similar view but showing the arrangement of parts when the oil in the barrel is to be removed therefrom.

Referring now to the drawing in detail, a portion of the working barrel of an oil pump is indicated by the numeral 1. The numeral 3 designates a hollow tubular member which is in the nature of a sand catcher. Secured on the open top of the tubular member 3 there is a cap member or nipple 2, to which the lower end of the pipe 1 is connected. The lower open end of the tubular member 3 has also secured thereto a hollow cap or nipple 4, the said nipple being directly connected to the flanged lower edge of a plate or partition 8 that is also connected to the member 3.

Arranged centrally in the lower portion of the sand catcher 3, passing through bearing openings in the partition 8, and in the bore there is an anchor pipe 5. The pipe is provided with apertures 7 through which the oil flows, and above the apertures with a fixed collar 6, a spring 6' surrounding the anchor pipe and bearing against the collar and against the lower end of the nipple 4.

The anchor pipe, above the partition plate 8 has secured thereon a fixed collar 9 designed to rest on a ring gasket 12 let in an annular depression that surrounds the

central opening in the partition plate 8. The partition plate is formed with a downwardly extending tubular extension 13, and the anchor pipe 5 is provided with apertures 14 which are normally concealed by 60 the sleeve 13 and the bore or opening in the partition 8.

Seated in the top of the anchor pipe there is a ball valve 11 enclosed by a slotted cage 10.

Secured on the outer wall of the partition 8 there are spring catches 15 designed, when the anchor pipe is raised in the sand catcher 3, to underlie the collar 9 and to hold the anchor pipe in the position illustrated in 70 Figure 2.

When the device is in pumping position, as illustrated in Figure 1, the anchor pipe 5 is moved outwardly through the member 3 by the spring 6' which causes the collar 9 75 to firmly seat on the gasket 12 to provide a tight joint between these elements and also a concealing means for the apertures 14. The pump is operated in the usual manner.

When the tubing is to be drawn, the working barrel is let down in the well so that the outer end of the anchor pipe 5 will contact the bottom of the well. This will cause the sand catcher 3 to be moved downwardly on the anchor pipe against the pressure of the 80 spring 6'. Such movement brings the apertures 14 in the anchor pipe above the partition 8 and also permits the spring catches 15 to underlie the collar 9 so that the anchor pipe and sand catcher are sustained in 90 the position illustrated in Figure 2. The oil remaining in the working barrel and in the sand catcher will flow through the perforations 14 and from thence through the anchor pipe and through the apertures 7 95 so that the oil will again enter the well and such oil, which otherwise is a total loss, is consequently saved.

Having described the invention, I claim:

1. In a well pumping apparatus, a working barrel, a sand catcher secured to the lower end thereof, a partition in the sand catcher above the lower end thereof, an anchor pipe movable through the said lower end and through said partition, said anchor pipe having spaced series of apertures, spring means influencing the anchor pipe in one direction whereby one of said series of apertures is covered by the partition, means 110

2
limiting the movement of the anchor pipe in such direction, and a caged valve on the upper end of the anchor pipe.

2. In a well pumping apparatus, a working barrel, a hollow sand catcher secured to the lower end of the barrel, a partition in the sand catcher having a central opening therethrough surrounded on its upper face by a compressible gasket and having its lower face provided with a depending sleeve which also surrounds said opening, an anchor pipe having spaced series of apertures arranged in the opening in the partition and passing through the lower end of the sand catcher, a fixed collar on the anchor pipe in contact with the gasket, spring

means influencing the anchor pipe whereby to cause the collar to frictionally engage the gasket and to retain the upper series of apertures concealed by the partition and the depending sleeve thereon, the other series of apertures being disposed below the sand catcher, spring catches on the partition designed when the anchor pipe is subjected to contact with the bottom of the wall and the sand catcher moved downwardly thereover to engage with the fixed collar to sustain the upper series of apertures in the anchor pipe above the partition, and a caged ball valve at the upper end of the anchor pipe. 30

In testimony whereof I affix my signature.
VAN HAMILTON.
